CONNECTER ACTUATING AND LOCKING DEVICE

Daniel W. Shiek, Aurora, Ill., assignor to The Miller-Bryant-Pierce Company, Aurora, Ill., a corporation of Illinois

Application October 26, 1932, Serial No. 639,727

22 Claims. (Cl. 200—42)

This invention relates to a connector actuating device and lock mechanism therefor, and particularly to a device for transmitting motion from the manually actuated portion thereof to the element to be operated, and to means for preventing operation of the manually actuated portion by unauthorized persons.

The illustrative embodiment of the present invention is shown in conjunction with, and for actuating the connector of an ignition switch operatively related to the contacts of an ignition coil adapted for use in the ignition system of an automobile.

One object of the present invention is to provide a combination lock mechanism which may be manually released to permit movement of a connector for any desired purpose as in the present instance, for example, to connect the terminals of an ignition coil.

Another object of the invention is to provide means for locking the manually operated portion of the device against movement when the connector is either in or out of contact connecting position.

Another object of the present invention is to provide a structure wherein a portion of the mechanism may be released and the connector moved out of contact engaging position without operating the manually actuated means employed for moving the connector into contact engaging position.

Another object of the invention is to provide a structure wherein the manually operated contact actuating means may be locked and the device protected against dismantling whether the connector is in or out of contact engaging position.

Another object of the invention is to provide a device wherein the manually actuated portion thereof may be released from locked position by the manipulation of a plurality or combination of elements for moving the contact connector in one direction only.

A further object of the invention is to provide means for retaining the manually operated means in a position to prevent operation of the locking means when desired.

A still further object of the invention is to improve devices of the character described in sundry details hereinafter referred to and particularly pointed out in the appended claims.

One embodiment of the present invention is shown for illustrative purposes in the accompanying drawings, in which:

Fig. 1 is a front elevational view of a structure illustrating portions of the present invention;

Fig. 2 is a longitudinal sectional plan view taken substantially as indicated by the line 2—2 of Figs. 1 and 3, and illustrating the application of the present invention to the actuating and controlling of the switch mechanism of an ignition coil;

Fig. 3 is a longitudinal sectional elevation of the structure illustrated in Figs. 1 and 2, and taken substantially as indicated by the lines 3—3 thereof;

Fig. 4 is a transverse sectional view taken on the line 4—4 of Fig. 3;

Fig. 5 is a transverse sectional elevation taken substantially as indicated by the line 5—5 in Figs. 2 and 3;

Fig. 6 is a transverse fragmentary sectional elevation taken substantially as indicated by the line 6—6 of Fig. 3;

Fig. 7 is a detailed view, partly in section, of a bracket for supporting an insulating disc and electrical connector as illustrated in Figs. 2, 3, 4 and 11, the view shown in Fig. 7 being taken as indicated by the line 7—7 of Fig. 3;

Fig. 8 is a front elevational view, partly in section, illustrating the actuating member in changed position, with the electrical connector, shown by dotted lines, in contact engaging position;

Fig. 9 is a detail sectional elevation showing a portion of the locking mechanism and taken substantially as indicated by the line 9—9 of Fig. 1;

Fig. 10 is also a detail sectional elevation showing a portion of the locking mechanism and taken substantially as indicated by the line 10—10 of Fig. 1; and

Fig. 11 is a perspective view of an assembly embodying a portion of the present invention and comprising a bearing member, bracket, insulating disc and connector carried thereby, and showing the relationship of a spring detent carried by the bracket, and operatively related to the bearing member for retaining the connector in contact engaging position.

Referring to the drawings, it will be observed that the illustrative embodiment of the invention is shown in conjunction with a spark coil indicated as a whole by the numeral 15 and comprising a body portion of insulating material 16 having the usual electrical contacts 17 mounted thereon, and that the present invention associated with the coil comprises a housing indicated as a whole by the numeral 18 surrounding the body of the coil 15 and extending a substantial distance beyond one end thereof.

The housing 18, in the present instance, com-

prises a tubular member 19, a flanged collar 21 secured thereto by means of rivets 22, a relatively heavy ring 23 secured to the flange of the collar 21 by means of rivets 24 (Fig. 2) and a facing or 5 finishing ring 26 secured to the ring 23 by means of screws 27 (Fig. 3), the flange of the collar 21 having ears 25 (Figs. 2 and 4) formed thereon for securing the device to a suitable support as, for example, to the instrument board of a motor 10 vehicle.

Mounted in the housing 18, in spaced relation with respect to the adjacent end of the coil 15 and contacts 17 mounted thereon, is a bearing member 28 secured against angular displacement with 15 respect to the housing 18 by means of annularly spaced projections 29 (Fig. 4) formed on the adjacent edges portion of the tubular member 19 and extending into annularly spaced notches or recesses 31 (Figs. 4 and 11) formed in the edge 20 of the bearing member 28.

Rotatably mounted in the bearing member 28 is a hollow shaft 32 (Figs. 2 and 7) having, at one end thereof, a reduced portion 33 on which is mounted, at one side of the bearing member 28, 25 a bracket 34 having a centrally positioned aperture formed therein to receive the reduced end portion 33 of the shaft 32, and having radially extending recesses into which a portion of the reduced end 33 is forced to provide a driving connection between the shaft 32 and the bracket 34 in a manner to insure rotation of the bracket 34 with the shaft 32, as clearly shown in Figs. 2 and 7.

Formed on the bracket 34 are a plurality of 35 annularly spaced substantially parallel arms 36 adapted to be positioned in annularly spaced notches or recesses 37 formed in a disc 38 of insulating material (Figs. 2, 3 and 11) adjacent a centrally positioned aperture 39 formed in the 40 insulating disc, the ends of the arms 36 being bent outwardly as indicated at 41 in Figs. 2 and 11 for securing the disc 38 against displacement with respect to the bracket 34.

Mounted on the disc 38 by means of fingers 45 42 engaging annularly spaced recesses 43 formed in the periphery of the disc 38 (Figs. 2, 3 and 11) is an electrical connector indicated as a whole by the numeral 44 formed of current conducting material and provided with a plurality of 50 spring fingers 46 having contact surfaces 47 formed thereon adjacent the free ends thereof and adapted for engagement with the contacts 17 of the coil 15. The connector 44 is also provided with a centrally disposed opening or aperture 48 (Figs. 2 and 11) adapted to receive the 55 outwardly bent portions 41 of the arms 36 in a manner to space the arms from the connector and to maintain the connector completely insulated from the bracket 34.

60 It will be observed that by such an arrangement the connector 44 is rigidly mounted on the insulating disc 38 in spaced relation with respect to the bracket 34, and that the resiliency of the spring fingers 46 serves to urge and maintain the 65 contact surfaces 47 in engagement with the coil contacts 17 when in contact therewith.

Secured to the opposite end of the hollow shaft 32 at the opposite side of the bearing member 28 is a fin supporting member 49 having a laterally 70 extending fin 51 (Figs. 3 and 4) mounted or formed thereon in radially spaced relation with respect to the axial line of said shaft 32, the fin supporting member 49 being secured to the shaft 32 by means of struck out portions 50 formed on 75 the shaft engaging radially extending recesses

formed in the member 49, as clearly shown in Fig. 2.

It will be observed from the foregoing description that as the fin supporting member 49 and hollow shaft 32 are rotated in the bearing member 28, the bracket 34, insulating disc 38 and electrical connector 44 will be rotated therewith in a manner to move the contact surfaces 47 of the connector 44 into and out of engagement with the coil contacts 17 as clearly shown in Fig. 5 where the contact surfaces 47 are out of engagement with the contacts 17, and in dotted lines in Fig. 8 where the contact surfaces 47 are in engagement with the coil contacts 17.

For rotating the connector 44 to move the contact surfaces 47 into engagement with the contacts 17 of the coil 15, a bearing or cam plate 52 is secured to the housing 18, preferably to the facing or finishing ring 26 thereof by means of screws 53 (Figs. 1, 2 and 8) and mounted adjacent the outer or exposed side of the plate 52 is a rotatable actuating member indicated as a whole by the numeral 54 adapted to cover the screws 53 when in normal position, and having a laterally extending portion or trunnion 56 extending through a circular aperture 57 formed in the plate 52 as clearly shown in Fig. 2. At the opposite side of the bearing or cam plate 52 and secured to the laterally extending portion or trunnion 56 of the actuating member 54 by means of a pin 58 is a bearing disc 59 having a step portion extending radially beyond the aperture 57 at one side of the plate 52 and having a reduced portion extending into the aperture 57 to obtain a bearing therein as clearly shown in Figs. 2 and 3. Mounted on the bearing disc 59 in radially spaced relation with respect to the central or axial portion thereof is a stud or lug 61 positioned to overlap and engage the fin 51 on the fin supporting member 49, as clearly shown in Figs. 3 and 4, when the actuating member 54 and bearing disc 59 are rotated in a clockwise direction (Figs. 1 and 4).

It will be observed from the foregoing description that with the parts described in their respective positions shown in Figs. 1 to 7, inclusive, and Fig. 11, the rotation of the actuating member 54 in a clockwise direction as indicated by the arrows 62 in Fig. 1, to the position shown in Fig. 8, the bearing disc 59 by reason of the pin 58 will be rotated and the stud 61 mounted thereon, by reason of its engagement with one edge of the fin 51 on the fin supporting member 49, will rotate the hollow shaft 32, bracket 34, insulating disc 38 and electrical connector 44 and move the contact surfaces 47 thereof into engagement with the coil contacts 17 as shown by dotted lines in Fig. 8, thereby establishing an operative connection between the contacts of the spark coil. After establishing this connection and upon releasing the actuating member 54, the stud 61, bearing disc 59 and actuating member 54 will be returned to their initial or normal position shown in Figs. 1, 2, 3, 4 and 6 by a spring 63 (Figs. 2, 3 and 6) having one 135 of its end portions positioned in a socket formed in the hub of the bearing disc 59 as illustrated in Fig. 6, and its opposite end portion hooked around a bolt 64 mounted in the bearing or cam plate 52 (Figs. 2 and 6).

For retaining the contact surfaces 47 of the connector 44 in engagement with the coil contacts 17 after the actuating member 54 has been released and returned to its normal or initial position by the spring 63, as above described, a 140

flat spring 66 is provided and shown, in the present instance, as formed integrally with the bracket 34 and extending outwardly and laterally therefrom. The flat spring 66 is provided at its outer free end with a detent or dog 67 adapted to enter and extend partially through a radially positioned aperture 68 formed in the bearing member 28 (Figs. 3, 4 and 11). When it is desired to disconnect the contacts 17, a release plunger 69, slidably mounted in an aperture 71 formed in the bearing or cam plate 52 and having its inner end portion extending into and partially through the aperture 68, may be pressed inwardly by the operator in a manner to push the detent 67 out of the aperture, after which a spring 72 (Figs. 2, 3 and 4) having one of its end portions extending through and secured to a lug 73 mounted on the fin supporting member 49, and its opposite end secured to a bolt 74 mounted on the bearing member 28, will act to rotate the fin supporting member 49 and hollow shaft 32, thereby returning the bracket 34, insulating disc 38 and connector 44 to their initial or normal positions, with the contact surfaces 47 out of engagement with the coil contacts 17 as shown in Fig. 5, the return movement of the parts being limited to a predetermined amount by a stop lug 76 carried by a portion of the bearing member 28 and extending into the path of a pair of laterally extending projections 77 and 78 formed on the bracket 34 as clearly shown in Fig. 7, the engagement of the projection 77 with the lug 76 serving to position the contact surfaces 47 of the connector 44 between the coil contacts 17 as illustrated in Fig. 5.

For securing the device in inoperative position and against operation by unauthorized persons, a lock mechanism is provided and shown in the present instance as mounted in the actuating member 54. The lock member of the present structure includes the bearing or cam plate 52 having a concentric cam surface 79 and an eccentric cam surface 81 formed adjacent its edge portion, see Figs. 1, 2 and 8, the said cam surfaces being adapted to be engaged by the end portion 82 of an arm indicated as a whole by the numeral 83 and pivotally mounted intermediate its ends on a pivot pin 84 carried by the actuating member 54, the opposite end portion 86 of the arm being adapted to engage a rectangular notch 87 formed in one edge of a locking bar 88 slidably mounted in the actuating member 54 as clearly shown in Figs. 1, 2 and 10. A spring 89 is wrapped around the head of the pivot pin 84 and operatively related to the end portion 82 of the arm 83 and to a portion of the actuating member 54 in a manner to urge the end portion 82 of the arm toward and into engagement with the cam surfaces 79 and 81, as shown in Figs. 1, 2 and 10.

The slidable locking bar 88 is provided on its opposite longitudinal edges with a plurality of longitudinally spaced recesses or notches 91 adapted to receive lugs 92 formed on a plurality of tumblers 93 (Figs. 1, 3 and 9), certain of the lugs 92 being shown in Fig. 1 as normally out of engagement with the notches 91 and certain other of the lugs 92 being shown normally in engagement with the notches formed in the slidable locking bar 88 for controlling the position thereof to prevent unauthorized operation of the device.

For controlling the position of the tumblers 93, a plurality of push buttons 94, 95, 96, 97, 98, 99, 100, 101 and 102 are slidably mounted in and po-

sitioned on opposite sides of the actuating member 54 and operatively related to the respective tumblers 93 by an annular groove and lug connection indicated at 103 in Fig. 9, the push buttons being adapted to be pressed inwardly against the action of springs 104 which normally hold the buttons in their distended or outward positions. It will be noted by reference to Fig. 1 that the lugs 92 of the tumblers 93 controlled by the push buttons 94, 100 and 97 are normally positioned in certain of the recesses 91 formed in the locking bar 88, thereby preventing a sliding movement thereof, and that by reason of the relationship and position of the pivoted arm 83 (Figs. 1 and 2) with respect to the locking bar 88 and the eccentric cam surface 81, any attempt to rotate the actuating member 54 in a clockwise direction (Fig. 1), to move the contact surfaces 47 of the connector 44 into engagement with the coil contacts 17, will be resisted by the eccentric cam surface 81, thereby preventing unauthorized operation of the device. It will be observed, however, that by pressing the push buttons 94, 100 and 97 inwardly, the lugs 92 on the tumblers 93 controlled by the push buttons 94, 100 and 97 will be moved out of engagement with their respective notches of the locking bar 88 and permit the bar to slide longitudinally of the actuating member 54 as the end portion 82 of the pivot arm 83 is cammed or moved outwardly by the eccentric cam surface 81 and onto the concentric cam surface 79 when the actuating member 54 is rotated in a clockwise direction as indicated by the arrows 62 in Fig. 1, thereby permitting the actuating member 54 to assume the position shown in Fig. 8 and moving the contact surfaces 47 of the connector 44 into engagement with the coil contacts 17, after which as previously explained, the contact surfaces 47 may be maintained in coil contact engaging position by the spring actuated detent 67 engaging the aperture 68 formed in the bearing member 28, and upon releasing the push buttons 94, 100 and 97, the actuating member 54 will be returned to its normal or initial position shown in Figs. 1, 2 and 3 under the influence of the spring 63 in the manner previously described, and by reason of the end portion 82 of the pivot arm 83 being maintained in contact with the cam surfaces 79 and 81 by the spring 89, and the engagement of the end portion 86 of the arm with the rectangular notch 87 formed in the locking bar 88, the bar will be moved longitudinally to its normal or initial position, at which time, the springs 104 will act to move the push buttons 94, 100 and 97 outwardly in a manner to position the lugs 92 of the tumblers 93 associated therewith in the adjacent notches or recesses 91 formed in the opposite edges of the locking bar 88. A more complete description of the structure relating to the locking bar, tumblers and push buttons, and the operation thereof may be obtained by reference to my patent for locking device, No. 1,652,644, issued December 13, 1927.

If found desirable, the lock mechanism carried by the actuating member 54 may be rendered inoperative to secure the connector 44 against rotation, as, for example, when parking the vehicle in a garage or the like, where it might be necessary for attendants to operate the engine of the vehicle, and for this purpose, a lever 106 is pivotally mounted on the cam plate 52 by means of a pivot pin 107, and is provided adjacent one of its ends with a hand crank 108 by which the lever may be readily rotated about its pivot, while

the opposite end of the lever is provided with a laterally extending projection 109 adapted to extend into the path of the actuating member 54 when the lever 106 is swung to the position illustrated in Fig. 8, thereby forming a stop for limiting the return or counterclockwise movement of the actuating member 54 as viewed in Fig. 8, and preventing the end portion 82 of the arm 83 from reaching a position adjacent the extreme lower 10 end of the eccentric cam surface 31. Such a limited movement of the member 54 and end portion 82 of the arm 83 prevents sufficient longitudinal movement of the locking bar 88 with respect to the actuating member 54 to enable the lugs 92 of 15 the tumblers 93 to enter the notches 91 of the locking bar 88 and thereby secure the bar against endwise movement.

It will be observed that by the arrangement described, the projection 109 will prevent movement of the actuating member 54 to its horizontal, normal or locking position, but will permit movement of the member 54 to an extent which will permit the contact surfaces 47 to be disengaged from the coil contacts 17, and that a garage attendant, although not knowing the proper combination of buttons to be pressed in order to release the lock mechanism, may rotate the actuating member 54 and contacts 47 into engagement with the coil contacts 17, thereby enabling him to operate the vehicle, after which the plunger 69 may be moved inwardly to force the detent 67 out of the aperture 68 formed in the plate 28 and permit the spring 72 to rotate the connector 44 in a counterclockwise direction (Fig. 8) and move the contact surfaces 47 out of engagement with the coil contacts 17.

It will be observed from the foregoing description that the present invention provides a novel construction and arrangement for operating a connector and for securely locking the connector against operation by unauthorized persons.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim and desire to secure by Letters 50 Patent is:

1. In a device of the class described, the combination of a housing, a rotatable connector mounted therein, said connector having a plurality of spring fingers and contact surfaces 55 formed integrally therewith, a manually actuated rotatable lock member outside said housing and operatively related to said connector for rotating the connector within the housing in one direction, lock mechanism for securing said member 60 against movement, and means for automatically moving the connector in the opposite direction independently of said lock member.

2. In a device of the class described, the combination of a housing, a rotatable connector mounted therein, a manually actuated rotatable lock member outside said housing and operatively related to said connector for rotating the connector within the housing in one direction, a combination lock mechanism for securing said member 70 against movement in a direction to rotate said connector, and resilient means for moving the connector in the opposite direction independently of said lock member.

3. In a device of the class described, the combination of a housing, a rotatable connector

mounted therein, a manually actuated rotatable lock member outside said housing and operatively related to said connector for manually rotating the connector within the housing in one direction, lock mechanism for securing said member 80 against movement in a direction to manually rotate said connector, and means for automatically moving the connector and manually actuated member in the opposite direction.

4. In a device of the class described, the combination of a housing, a rotatable connector mounted therein, a manually actuated rotatable lock member outside said housing, cooperable means operatively related to said connector and member, respectively, for rotating the connector when said lock member is rotated in one direction, and resilient means operatively related to said connector and member, respectively, for automatically rotating the connector and lock member in the opposite direction.

5. In a device of the class described, the combination of a housing, a movable connector mounted therein, a manually actuated member outside said housing, relatively movable elements cooperable with each other and operatively related to said connector and member, respectively, for positively moving the connector when said manually actuated member is moved in one direction, independent resilient means operatively related to said connector and manually actuated member, respectively, for moving the connector and member in the opposite direction, and lock mechanism for securing said manually actuated member against movement in a direction to rotate said connector.

6. In a device of the class described, the combination of a housing, a bearing member mounted therein, a shaft rotatably mounted in said member, a connector operatively related to and adapted to rotate with said shaft, a fin-supporting member having a fin mounted thereon secured to said shaft, an apertured bearing plate mounted in said housing, an actuating member on one side of said plate, a bearing disc at the opposite side of the plate secured to said actuating member and rotatably mounted in the aperture formed in said plate, a stud mounted on said disc in a manner to engage said fin for rotating said fin-supporting member, shaft and connector when said actuating member and bearing disc are 110 rotated.

7. In a device of the class described, the combination of a housing, a bearing member mounted therein, a shaft rotatably mounted in said member, a connector operatively related to one end 130 of said shaft at one side of said member and adapted to rotate with said shaft, a fin-supporting member having a fin mounted thereon secured to the other end of said shaft at the opposite side of said bearing member, an apertured bearing plate mounted in said housing, an actuating member on one side of said plate, a bearing disc at the opposite side of said plate secured to said actuating member and rotatably mounted in the aperture formed in said plate, a stud 140 mounted on said disc in a manner to engage said fin for rotating said fin-supporting member, shaft and connector in one direction when said actuating member and disc are rotated in one direction, and resilient means operatively related to 145 said fin-supporting member and disc, respectively, for rotating said connector and actuating member in the opposite direction.

8. In a device of the class described, the combination of a housing, a bearing member mounted

- therein, a shaft rotatably mounted in said member, a connector operatively related to one end of said shaft at one side of said member and adapted to rotate with said shaft, a fin-supporting member having a fin mounted thereon secured to the other end of said shaft at the opposite side of said bearing member, an apertured bearing plate mounted in said housing, an actuating member on one side of said plate, a bearing disc at the opposite side of said plate secured to said actuating member and rotatably mounted in the aperture formed in said plate, a stud mounted on said disc in a manner to engage said fin for rotating said fin-supporting member, shaft and connector in one direction when said actuating member and disc are rotated in one direction, resilient means for moving said stud out of engagement with said fin when said actuating member is released, retaining means operatively related to said connector and bearing member for retaining the connector in position after the stud is moved from engagement with said fin, manually operated means for releasing said retaining means, and resilient means operatively related to said fin-supporting member and bearing member for rotating said connector in the opposite direction when said retaining means is released.
9. In a device of the class described, the combination of a housing, a bearing member having a centrally disposed aperture formed therein and mounted in said housing, a shaft rotatably mounted in said member, a bracket mounted on one end of said shaft at one side of said member and adapted to rotate with the shaft, a disc of insulating material carried by said bracket, a connector mounted on said disc in spaced relation with respect to said bracket and connected to the disc in a manner to rotate therewith and with said bracket and shaft, a fin-supporting member having a fin mounted thereon secured to the other end of said shaft at the opposite side of said member, an apertured bearing plate mounted in said housing, an actuating member on one side of said plate, a bearing disc at the opposite side of said plate secured to said actuating member and rotatably mounted in the aperture formed in said plate, a stud mounted on said bearing disc in a manner to engage said fin for rotating said fin-supporting member, shaft and connector in one direction when said actuating member and bearing disc are rotated in one direction, resilient means for moving said stud out of engagement with said fin when said actuating member is released, a spring actuated detent mounted on said bracket and engageable with a portion of said bearing member for retaining the connector in position after the stud is moved from engagement with said fin, manually operated means slidably mounted in said bearing plate and engageable with said detent for moving it out of the radially spaced aperture formed in said bearing member for releasing the detent, and resilient means operatively related to said fin-supporting member and bearing member for rotating said bracket, insulating disc and connector in the opposite direction when said detent is released.
10. In a device of the class described, the combination of a housing, a bearing member having a centrally disposed aperture and a radially spaced aperture formed therein and mounted in said housing, a shaft rotatably mounted in said member, a bracket mounted on one end of said shaft at one side of said member and adapted to rotate with the shaft, a disc of insulating material carried by said bracket, a connector mounted on said disc in spaced relation with respect to said bracket and connected to the disc in a manner to rotate therewith and with said bracket and shaft, a fin-supporting member having a fin mounted thereon secured to the other end of said shaft at the opposite side of said member, an apertured bearing plate mounted in said housing, an actuating member on one side of said plate, a bearing disc at the opposite side of said plate secured to said actuating member and rotatably mounted in the aperture formed in said plate, a stud mounted on said disc in a manner to engage said fin for rotating said fin-supporting member, shaft and connector in one direction when said actuating member and disc are rotated in one direction, resilient means for moving said stud out of engagement with said fin when said actuating member is released, a spring actuated detent mounted on said bracket and engageable with said bearing member for retaining the connector in position after the stud is moved from engagement with said fin, manually operated means slidably mounted in said bearing plate and engageable with said detent for moving it out of the radially spaced aperture formed in said bearing member for releasing the detent, and resilient means operatively related to said fin-supporting member and bearing member for rotating said bracket, insulating disc and connector in the opposite direction when said detent is released.
11. In a device of the class described, the combination of a housing, a bearing member having a centrally disposed aperture and a radially spaced aperture formed therein and mounted in said housing, a shaft rotatably mounted in said member, a bracket having laterally extending projections formed thereon mounted on one end of said shaft at one side of said member and adapted to rotate with the shaft, a disc of insulating material carried by said bracket, an electrical connector mounted on said disc in spaced relation with respect to said bracket and connected to the disc in a manner to rotate therewith and with said bracket and shaft, spring fingers having contact surfaces formed integrally with said connector, a fin-supporting member having a radially spaced fin formed integrally therewith secured to the other end of said shaft at the opposite side of said member, an apertured bearing plate mounted in said housing, an actuating member on one side of said plate, a bearing disc secured to said actuating member and rotatably mounted in the aperture formed in said plate, a radially spaced stud mounted on said bearing disc in a manner to engage said fin for rotating said fin-supporting member, shaft, bracket and connector in one direction when said actuating member and bearing disc are rotated in one direction, resilient means for moving said stud out of engagement with said fin when said actuating member is released, a spring actuated detent mounted on said bracket and engageable with the radially spaced aperture formed in said bearing member for retaining the connector in position after the stud is moved from engagement with said fin, a manually operated plunger slidably mounted in said bearing plate and bearing member and engageable with said detent for moving it out of the radially spaced aperture formed in said bearing member for releasing the detent, resilient means operatively related to said fin-supporting member and bearing member for

rotating said bracket, insulating disc and connector in the opposite direction when said detent is released, and a stop lug carried by said bearing member and extending into the path of movement of the projections formed on said bracket for limiting the movement of the bracket, insulating disc and connector.

12. In a device of the class described, the combination of a housing, a bearing member mounted therein, a shaft rotatably mounted in said member, a connector operatively related to and adapted to rotate with said shaft, a cam plate having an aperture formed therein mounted in said housing said plate having concentric and eccentric cam portions formed thereon, an actuating member on one side of said plate, a bearing disc at the opposite side of the plate secured to said actuating member and rotatably mounted in the aperture formed in said plate, lock mechanism carried by said actuating member comprising a locking bar having a rectangular notch formed therein and a plurality of spaced recesses formed in one edge thereof, an arm pivotally mounted on said actuating member and engageable with the notch formed in said bar and with said concentric and eccentric cam portions, a plurality of tumblers engageable with said recesses, a plurality of buttons for actuating said tumblers to permit rotation of said actuating member and bearing disc, and means mounted on said disc and operatively connectible to said shaft for rotating said connector when said actuating member and disc are rotated.

13. In a device of the class described, the combination of a housing, a bearing member mounted therein, a shaft rotatably mounted in said member, a connector operatively related to and adapted to rotate with said shaft, a cam plate having concentric and eccentric cam portions formed thereon adjacent its outer edge, said plate being secured in said housing and having an aperture formed therein adjacent its central portion in substantially axial alignment with said shaft, an actuating member on one side of said plate outside said housing, a bearing disc at the opposite side of the plate secured to said actuating member and rotatably mounted in the axially aligned aperture formed in said plate, lock mechanism carried by said actuating member comprising a locking bar having a rectangular notch formed therein adjacent one end thereof and a plurality of longitudinally spaced recesses formed in one edge thereof, an arm pivotally mounted on said actuating member and engageable with the notch formed in said bar and with said concentric and eccentric cam portions, a plurality of tumblers engageable with said recesses for controlling the position of said bar, a plurality of buttons for moving said tumblers out of engagement with said recesses to permit rotation of said actuating member and bearing disc, and means mounted on said disc and operatively connectible to said shaft for rotating said connector when said actuating member and disc are rotated in one direction.

14. In a device of the class described, the combination of a housing, a bearing member mounted therein, a shaft rotatably mounted in said member, a connector operatively related to and adapted to rotate with said shaft, a cam plate having an aperture formed therein mounted in said housing, said plate having concentric and eccentric cam portions formed thereon adjacent its outer edge, an actuating member on one side of said plate outside said housing, a bearing disc at the opposite side of the plate secured to said

actuating member and rotatably mounted in the aperture formed in said plate, lock mechanism carried by said actuating member comprising a locking bar slidably mounted in the actuating member and having a notch formed therein adjacent one end thereof and a plurality of longitudinally spaced recesses formed in its opposite longitudinal edges, an arm pivotally mounted on said actuating member and engageable with the notch formed in said bar and with said concentric and eccentric cam portions, a plurality of tumblers engageable with said recesses, a plurality of buttons at opposite sides of the actuating member for controlling the position of said tumblers to permit rotation of said actuating member and bearing disc, and means mounted on said disc and operatively connectible to said shaft for rotating said connector when said actuating member and disc are rotated in one direction.

15. In a device of the class described, the combination with a spark coil having a plurality of electrical contacts mounted in its body portion, of a housing surrounding one end of said body portion, a bearing member mounted in said housing, a shaft rotatably mounted in said member, a connector operatively related to and electrically insulated from said shaft and adapted to rotate therewith, said connector having a plurality of contact surfaces engageable with a portion of the coil body and said coil contacts, a cam plate having an aperture formed therein mounted in said housing, said plate having concentric and eccentric cam portions formed thereon, an actuating member on one side of said plate, a bearing disc at the opposite side of the plate secured to said actuating member and rotatably mounted in the aperture formed in said plate, lock mechanism carried by said actuating member comprising a locking bar having a notch formed therein and a plurality of spaced recesses formed in one edge thereof, an arm pivotally mounted intermediate its ends on said actuating member and engageable at one of its ends with the notch formed in said bar and at its opposite end with said concentric and eccentric cam portions, a plurality of tumblers engageable with said recesses, a plurality of buttons for actuating said tumblers to permit rotation of said actuating member and bearing disc, and means mounted on said disc and operatively connectible to said shaft for rotating said connector to electrically connect the coil contacts when said actuating member and disc are rotated in one direction.

16. In a device of the class described, the combination with a spark coil having a plurality of electrical contacts mounted in its body portion, of a housing surrounding one end of said body portion and extending beyond the end thereof, a bearing member mounted in said housing, a shaft rotatably mounted in said member, a connector operatively related to and electrically insulated from said shaft and adapted to rotate therewith, said connector having a plurality of contact surfaces engageable with said coil contacts, a cam plate having an aperture formed therein mounted in said housing, said plate having concentric and eccentric cam portions formed thereon, an actuating member on one side of said plate, a bearing disc at the opposite side of the plate secured to said actuating member and rotatably mounted in the aperture formed in said plate, lock mechanism carried by said actuating member comprising a lock bar slidably mounted in the actuating member and having a notch formed in one edge adjacent one of its end por-

- tions and a plurality of longitudinally spaced recesses formed in its opposite edges, an arm pivotally mounted on said actuating member and engageable with the notch formed in said bar and 5 with said concentric and eccentric cam portions, a plurality of tumblers slidably mounted in said actuating member and engageable with said recesses, a plurality of spring pressed buttons mounted in said actuating member for controlling 10 the position of said tumblers to permit movement of said bar under the influence of said arm against said cam surfaces as the actuating member is turned to rotate said bearing disc, and means mounted on said disc and operatively 15 connectible to said shaft for rotating said connector when said actuating member and disc are rotated in one direction.
17. In a device of the class described, the combination with a spark coil having a plurality of 20 electrical contacts mounted in its body portion, of a housing surrounding one end of said body portion, a bearing member mounted in said housing, a shaft rotatably mounted in said member, an electrical connector operatively related to 25 and electrically insulated from said shaft and adapted to rotate therewith on one side of said bearing member, said connector having a plurality of spring fingers and contact surfaces mounted thereon engageable with said coil contacts, a fin supporting member having a fin 30 mounted thereon secured to said shaft at the opposite side of said bearing member, a cam plate having an aperture formed therein secured in said housing, said plate having concentric and eccentric cam portions formed thereon, an actuating member on one side of said plate, a bearing disc at the opposite side of the plate secured to said actuating member and rotatably mounted in the aperture formed in said plate, lock mechanism 35 carried by said actuating member comprising a locking bar having a notch formed therein and a plurality of spaced recesses formed in its opposite edges, an arm pivotally mounted intermediate its ends on said actuating member and engageable at one of its ends with the notch 40 formed in said bar and at its opposite end with said concentric and eccentric cam portions, a plurality of tumblers engageable with said recesses, a plurality of push buttons on opposite sides of said actuating member for moving said tumblers out of engagement with said recesses to 45 permit the sliding of said locking bar and the rotation of said actuating member and bearing disc, and a stud mounted on said disc and engageable with the fin of the fin-supporting member secured to said shaft for rotating said connector when said actuating member and disc are rotated in one direction.
18. In a device of the class described, the combination of a housing, a rotatable connector mounted therein, a manually actuated rotatable lock member outside said housing and operatively related to said connector for rotating the connector within the housing in one direction, lock mechanism for securing said member in its normal position only and against movement in a direction to rotate said connector, resilient 50 means for moving the connector and manually actuated member in the opposite direction toward their normal positions, and a manually adjustable stop for preventing said manually actuated member from assuming its normal position. 80
19. In a device of the class described, the combination of a housing, a rotatable connector mounted therein, a manually actuated rotatable member outside said housing and operatively related to said connector for rotating the connector within the housing in one direction, lock mechanism mounted on said manually actuated member for securing the member in its normal position only and against movement in a direction to rotate said connector, a pair of springs for moving the connector and manually actuated member respectively in the opposite direction toward their normal positions, and a manually adjustable stop for preventing said manually actuated member from assuming its normal position and preventing the operation of said lock mechanism. 85
20. In a device of the class described, the combination with a plurality of contacts, of a housing surrounding said contacts, a rotatable connector mounted in said housing and having a plurality of surfaces engageable with said contacts, a manually actuated member operatively related to said connector and rotatable in one direction outside said housing for rotating the connector 100 in one direction within the housing to position said surfaces in engagement with said contacts, resilient means for moving said member in the opposite direction, means for retaining said surfaces in contact engaging position after said 105 manually actuated member has been moved in said opposite direction, lock mechanism for securing said member against movement in a direction to rotate said connector when the said surfaces are either in or out of engagement with said contacts, means for releasing said retaining means, and resilient means for rotating the connector and said surfaces in the opposite direction after said retaining means is released. 110
21. In a device of the class described, the combination of a housing, movable contact surfaces mounted within said housing, an actuating member outside said housing and operatively related to said contact surfaces for moving the surfaces within said housing, lock mechanism for securing 115 said actuating member against movement, and means operative at will to render said lock mechanism inoperative. 120
22. In a device of the class described, the combination of a housing, movable contact surfaces mounted within said housing, an actuating member outside said housing and operatively related to said contact surfaces for moving the surfaces within said housing, lock mechanism mounted in said actuating member for securing said actuating 125 member against movement and means operative at will for limiting the movement of said actuating member to render said lock mechanism inoperative without effecting the operation of said actuating member to move said contact surfaces. 130
- 135
